GARMENT AND MOISTUREPROOF COVER MEANS

John R. Lankenau, Brookline, Mass.

Application July 15, 1937, Serial No. 153,771

1 Claim. (Cl. 128—284)

My present invention relates to garments, particularly infants' undergarments of the diaper and like type, and to cover means therefor of rubber or like composition including novel securing 5 or attaching features. Among its main objects are to provide a simplified and otherwise improved garment of the class described, and which is adapted to serve as a combined diaper and moisture-proof protector, the latter having the 10 similar purpose as the rubber pant, and to supply such protector element that may readily be assembled with or removed from a diaper or other pant-like garment, as required. As to all common subject matter this application is a continuation in part of my copending application 15 Serial No. 143,767, filed May 20, 1937.

In the drawing illustrating by way of example one embodiment of the invention,

Fig. 1 is a plan view of one form of diaper having a cover or protector applied thereto in accordance with the invention, the assembly being shown in flat position, outside uppermost;

Fig. 2 shows the assembly of Fig. 1 as in one adjusted position for wear; and

Fig. 3 is a greatly enlarged view of one attaching formation for the cover element of thin sheet rubber or like composition.

Referring now more particularly to the drawing, and first to Figs. 1 and 2, the combination 30 garment as there illustrated comprises a fabric element or diaper proper, in this instance of a general form resembling that of an hourglass. Said element includes a rear section 20, seen at the lower portion of Fig. 1, and a connected front section 22, each having an upper, waist or band portion 24 and 26 respectively and an intermediate connecting or leg portion tapering oppositely toward each other and joining at their narrower parts, providing reentrant formations 40 at the sides of the garment adapted to form leg openings in the wearing position of the garment as illustrated in Fig. 2. This infants' or diaper type garment may be the same as that more fully described and claimed in my copending 45 application above identified.

Similarly as in said copending application the upper or waist portions 24 and 26 of the rear and front sections 20, 22 are provided with means for securing them together in wearing position, such 50 means being of the button type, one of the sections carrying the button element and the other having cooperating buttonhole formations. In the illustrated example the upper part 26 of the front section 22 has at each side portion a series of 55 elongated eyelets 27 for receiving at variable posi-

tions the novel button-carrying or fastener device of said copending application, one of which is indicated at 30 at the upper right portion of Fig. 1.

Such fastening device comprises a strip of soft 5 flexible fabric material adapted to be looped through any selected pair of the eyelets 27. This strip has a button 31 adjacent one end portion and one or more buttonholes spaced lengthwise of the strip from the button, whereby the strip 10 may be buttoned upon itself, to anchor the button detachably in operative position on the garment, for reception in a buttonhole formation of the other main garment section, such as one of those indicated at 33 at the lower left portion of Fig. 1. 15 A plurality of such buttonhole formations 33 are provided at each side of the particular section, herein the rear section 20, any one of which is capable of receiving the securing button 31 at the corresponding side of the garment, for the 20 purposes of adjustment, all as more fully explained in my said copending application. The eyelets or buttonhole formations 27 for removably receiving the button attaching strips 30, 25 which latter desirably extend transversely of the garment, are preferably disposed with their longitudinal axes vertical, while the series of buttonhole formations 33 in the other section desirably have their major axes horizontal or transverse of the garment, in the direction of the major 30 strains.

Additional means may be provided for securing together the leg portions of the garment at the corresponding sides, also with wide latitude for adjustment. As in said copending application, 35 said means as here shown comprises a pair of securing ties or tapes 35, 35 stitched at one of their ends upon the outer face of the front section 22, at the opposite sides of its vertical center line. Similar ties 36, 36 are provided on the 40 other or rear section. Thus at each side of the garment there is a pair of ties 35 and 36, one on the front and one on the rear section, adapted for tying together as seen in Fig. 2 to adjust and confine the leg portions of the garment in wearing 45 position. The ties on the front section may have their inner ends extended to provide loops 35a, 35a for the attachment of stockings or other articles.

At one face of the described diaper element 50 proper, herein shown as the outer face, I provide in novel combination therewith a cover, protecting element, or protector having novel means for securing it in position flatwise against the diaper. It will be understood with reference to 55

Figs. 1 and 2 that such cover or protector, illustrated as a whole by the numeral 40, is shown broken away at the upper right and lower left corner portions in Fig. 1, and also that the tie 5 means above described extend outwardly through apertures provided in the cover element at appropriate locations, as will be later described herein.

Referring now more particularly to the cover 10 means 40, the latter comprises a single sheet element of thin light-weight, flexible, moisture-proof material, generally rubber or a rubber composition such for example as heretofore employed in the formation of infants' rubber pants having 15 a circumferentially continuous waist portion. Such material desirably is of a thickness comparable to and preferably not substantially exceeding that of ordinary paper. The sheet 40 as a whole is of a shape and size to conform to and 20 cover the major portion of the particular diaper, and as herein illustrated is of the full size and same shape as the latter, to overlie its entire area. This thin rubber protecting element 40 is finished along its entire periphery with a bead-like edging 41 which may be formed by folding over and uniting the extreme outer edge in the manner of a fine tube or hem of the rubber material.

At the portion of the cover 40 overlying the 25 front diaper section 22, the section which in the illustrated example carries the detachable button elements 30, 31, the cover is provided with attaching formations for the passage of the buttons 31, a series of three such formations 42 being seen at the upper left portion in Fig. 1, the 30 central formation being covered by the button 31 extending through it on the underlying diaper element. In the particular example shown the two series of button-attaching eyelets or button-holes 27, at the two sides of the waist portion 35 in of the front section 22, each include four such formations. The button carrier for each series 40 may be secured in the pair of eyelets at the left of the series, or in the central pair as illustrated 45 in Fig. 1, or in the right hand pair, making in this case three different positions of adjustable attachment for the button. Accordingly the button receiving apertures 42 in the cover element 40 are three in number, in each series, one for 50 each adjusted position of the corresponding button on the diaper.

Similarly, on the other section of the cover element, I provide at each side a series of button receiving formations 43, herein three in number 55 in each series, corresponding to the number of buttonholes 33 at each side. The apertures for the passage of the securing ties 35 and 36 are located at the appropriate points adjacent the inner ends of the ties, as indicated at 44, 44 and 60 45, 45. The apertures in the cover element 40 as here referred to are of a general elongated shape and are arranged to be parallel with the corresponding underlying formations of the diaper, or, in the case of the tape passages, to extend 65 in the direction of the width of the tapes, it being noted that the front tapes 35 are attached to the diaper with their width extending transversely of the latter, while the rear tapes 36 are attached at right angles to such position. 70 The passages 45 in the rear section of the cover element accordingly extend vertically rather than horizontally as in the case of the front apertures 44.

Each individual aperture or receiving formation 75 in the cover element 40 preferably is of the

novel construction which I will now describe, with reference more particularly to Fig. 3. As previously indicated the rubber or rubber composition material of the cover element is of general paper thinness and hence is liable to tear if perforated at any point, in the absence of some provision to the contrary. To provide attaching apertures in connection with which this tendency is overcome, in a simple and inexpensive manner, with avoidance of special reinforcements and additional expensive vulcanizing operations, I have devised the novel structure of aperturing formation as represented in Figs. 1 and 2 and upon a greatly enlarged scale in Fig. 3.

Referring to the latter, such formations each 15 comprise a central slot 50 extending in the desired direction and terminating at each end in a substantially circular enlargement or terminal portion 51, 51. The edges of the latter circular terminal portions 51 desirably are merged into 20 the end edges of the intermediate slot formation 50, as by rounding them off slightly, as indicated at 52, 52. Such aperture as a whole may be stamped, died, or otherwise formed in a single operation, it being noted that the intermediate 25 portion 50 is more than a mere slit, a certain amount of material being bodily removed. The lateral extent of the material removed in any case, however, is substantially less than the diameter of the terminal portions 51, so that between the latter there are provided opposed shallow flaps or tab like members 53, 53 carried by the main body of the cover sheet itself. The over-all length of each such aperture from the outer end of one terminal portion to the corresponding end of the other one desirably is somewhat less than the diameter of a button intended to be passed through the aperture, so that generally the aperture is completely covered by the button, as seen at the upper left in Fig. 1. After 40 a button has been passed through one of such apertures the two opposed flaps 53, 53 which extend throughout the major length of the aperture are adapted to engage inwardly against the threads or other attaching means of the button, 45 substantially closing the aperture as well as tending to hold the cover element in position relative to the button and the underlying garment.

The operation of the non-tear attaching means or formations provided in the thin rubber cover element in accordance with my invention will readily be understood in connection with the illustration in Fig. 3. As previously noted a mere cut or slit made in the material such as referred to will quickly tear under stretching, whether the stretching is lengthwise or crosswise the slit, and particularly in the latter case. But by reason of the slotted construction, with the removal of material, generally to a width of the order of $\frac{1}{4}$ to $\frac{1}{2}$ of an inch depending upon the desired total size for the aperture and that of the cooperating button or other attaching means, and due to the enlarged circular terminal portions, the strains are distributed over a substantial area adjacent the aperture.

Instead of a single line of strain coincident with a slit, strains tending to stretch the rubber lengthwise of the aperture are directed along spaced lines, at two sides of the aperture and are distributed about the periphery of the terminal enlargements 51, 51, the latter assuming the shape, under such longitudinal strains, as indicated by the dotted lines at 51^a, 51^a, Fig. 3. In this instance it is noted that the facing edges of the tab members 53 are drawn inwardly toward 75

each other. If the stretching is carried beyond the point indicated at 51^a said tabs further approach or overlap each other, if no button is present to prevent. By reason of the disclosed 5 aperture construction, longitudinal strains and stretching actions of any degree likely to occur in normal use of the cover element are withstood without tearing, and without special reinforcement in the region of the aperture, far beyond 10 any stretching action possible, for example, with a mere slit, which promptly tears, generally cross-wise, at the slot ends.

Likewise, in the direction transversely of the aperturing formation, the lines of pull are again 15 distributed throughout the entire periphery of the terminal formations. If the rubber material is engaged near the two sides of the aperture and pulled outwardly in opposite directions the aperture assumes a shape such as represented by the 20 dotted lines at 51^b, 51^b. The effect in general is to open out the terminal enlargements laterally, distributing the strains along their entire edges, in contrast to concentrating them at a single point such as at each end of a slot.

25 In actual practice it has been found that thin rubber or like composition cover elements in accordance with my invention will stand use and manipulation, including daily attaching and disconnecting from the diaper elements employed 30 in combination with them, over substantial periods and are little or no more likely to wear out, by tearing or otherwise, in the region of the apertures than at other points upon the cover.

It will be understood that the cover element 35 equipped with the attaching formations in accordance with my invention may be variously shaped and dimensioned, for use with diapers or other garments of various types, the apertures being provided at appropriate points. Merely as 40 one further example, the cover or protector element is equally useful with a diaper of general

triangular or three-pointed construction such as illustrated in Figs. 9 and 10 of my said copending application, apertures being provided in the cover at corresponding points as therein illustrated for the passage of the single securing button 50 and 5 for the front and rear tie means.

In combination with diapers or other garments otherwise shaped, the apertures in the thin rubber cover element will be located appropriately for the passage of the securing or attaching 10 means in the particular instance.

My invention is not limited to the particular embodiment thereof illustrated and described herein, and I set forth its scope in my following claim:

15 In a garment of the diaper type, in combination, a fabric element having front and rear sections each including an upper portion and a connecting leg portion, button means at the upper portion of one section engageable with button-hole formations on the upper portion of the other section, for securing them together in wearing position, a moisture-proof cover means overlying 20 said fabric element, said means comprising a sheet of thin rubber material of a size and shape 25 to cover substantially the entire area of said fabric element, and means for retaining said elements in position relative to each other, including one or more buttons and cooperating button-holes on the fabric element, and button-receiving 30 aperture formations in said thin rubber cover element adjacent each such button and buttonhole, for the passage of the corresponding button, each such formation in said thin rubber element comprising a slot of a length approximating the diameter of the button to be received, said slot merging at each end into a substantially circular 35 terminal portion symmetrically disposed relative to the longitudinal axis of the slot and of a diameter exceeding the width of the latter.

JOHN R. LANKENAU.
